US0D1059302S

(12) **United States Design Patent** (10) Patent No.: **US D1,059,302 S**
(45) Date of Patent: ** Jan. 28, 2025

(54) **SWITCH HOUSING**

(71) Applicant: **Xiandong Zheng**, Jinhua (CN)

(72) Inventor: **Xiandong Zheng**, Jinhua (CN)

(**) Term: **15 Years**

(21) Appl. No.: **35/517,674**

(22) Filed: **Jun. 14, 2023**

(80) **Hague Agreement Data**

Int. Filing Date: **Jun. 14, 2023**

Int. Reg. No.: **DM/229807**

Int. Reg. Date: **Jun. 14, 2023**

Int. Reg. Pub. Date: **Jun. 30, 2023**

(51) LOC (15) Cl. **13-03**

(52) U.S. Cl.

USPC **D13/152**

(58) **Field of Classification Search**

USPC D13/152, 158, 169, 165, 110, 184, 199;
D26/142

CPC H03K 17/9505; H05K 5/00
